CIRCUITS FOR GENERATING ELECTRICAL IMPULSES

Eric Lawrence Casling White, Iver, England, assignor to Electric & Musical Industries Limited, Hayes, England, a company of Great Britain

Application February 3, 1948, Serial No. 6,049
In Great Britain February 4, 1947

3 Claims. (Cl. 250—36)

1

This invention relates to circuits for generating electrical impulses and has for its object to provide an improved circuit capable of generating impulses of very stable duration.

According to the invention there is provided a circuit for generating electrical impulses comprising a pair of electron discharge valves each having a cathode, control electrode and anode, said devices being connected at their cathodes to an electrical delay line and being so coupled that said circuit generates electrical impulses with a duration determined substantially only by the delay of said delay line.

In order that the said invention may be clearly understood and readily carried into effect it will now be more fully described with reference to the accompanying drawings, in which:

Figure 1 illustrates a circuit according to one embodiment of the invention, and

Figure 2 illustrates a circuit according to another embodiment of the invention.

Referring now to Figure 1, 1 and 2 are valves each having a cathode, control electrode and anode. Resistances 3 and 4 are connected in the cathode circuits respectively of valves 1 and 2 and the cathodes of valves 1 and 2 are coupled by a coupling circuit comprising resistance 5 and delay network 6 whose input terminals 7 and 8 are connected in series with resistance 5. At the end of said delay network remote from said input terminals said delay network is open-circuited. Thus the terminals 9 and 10 at the remote end of said network are left unconnected.

To cause said circuit to be capable of generating impulses, the anode circuit of valve 1 is provided with an anode load resistance 11 connected to the positive terminal of a source of anode current shown conventionally at 12 and the anode of valve 1 is coupled to the control electrode of valve 2 by coupling capacity 13. The control electrode of valve 2 is connected through resistance 14 to a point of suitable bias potential. The impulses generated by the circuit may be derived from the load resistance 15 connected to the anode of valve 2 and which is also connected to said source 12.

In one use of the circuit according to the invention regularly repeating controlling impulses of negative sense indicated at 16 may be applied to the control electrode of valve 1 so that an impulse is generated by the circuit only upon the incidence of a controlling impulse. The circuit is arranged so that in the intervals between the generated impulses valve 1 is conducting and valve 2 is non-conducting. Thus, upon the incidence of one of said controlling impulses the

2

current in valve 1 is reduced and in consequence the potential at the anode of valve 1 is increased. This increase of potential is communicated to the control electrode of valve 2 through capacity 13 and valve 2 is rendered conducting. Thus, the cathode potential of valve 2 is caused to rise, and, by virtue of the coupling between the cathodes of said valves, valve 1 is rendered non-conducting. At the same time an impulse whose amplitude may be suitably proportioned by correctly selecting the value of resistance 5 is caused to propagate along the delay network 6 towards its remote end from which end said impulse is reflected so as to cause valve 1 to return to the conducting condition upon the incidence of the reflected impulse back at terminals 7 and 8. When valve 1 is again rendered conducting, valve 2 is caused to cease to conduct by virtue of the coupling between the anode of valve 1 and control electrode of valve 2 and the circuit returns to its initial condition with valve 1 conducting and valve 2 non-conducting.

In the arrangement thus described the time constant of the coupling circuit comprising capacity 13 and resistance 14, said time constant being effective at the control electrode of valve 2, is made longer than the intervals between said controlling impulses. If desired, however, the coupling between the anode circuit of valve 1 and the control electrode of valve 2 may be such as to pass direct current.

Figure 2 of the drawings illustrates a further embodiment of the invention, the elements shown in Figure 2 which correspond to those shown in Figure 1 being given the same reference numerals. In this embodiment of the invention the cathode resistances 3 and 4 are omitted and the cathodes are connected together as shown and are connected to the input terminals 7 and 8 of the delay line 6. The delay line 6 thus presents at its input terminals 7 and 8 an impedance common to the cathode circuits of the valves 1 and 2. The terminals 9 and 10 of the delay line 6 are effectively short-circuited. The control electrode of the valve 1 is biased by means of a resistance 17 connected to a suitable source of potential which is arranged so that the valve 1 is conducting and is rendered non-conducting on the application of a negative controlling impulse to the control electrode of the valve. When a negative controlling impulse is applied to the valve 1 the potential of the anode of the valve increases, this increase of potential being communicated to the control electrode of the valve 2 through the coupling capacity 13 so that the valve 2 which was previously non-conducting is

rendered conducting. The cathode potential of the valve 2 is thus caused to rise and by virtue of the connection between the cathodes of the two valves, valve 1 is held non-conducting and at the same time an impulse is propagated along the delay line 6 and is reflected from the short-circuited end of the delay line in inverted sense. When the reflected impulse reaches the terminals 7 and 8 the cathode of valve 1 is driven negatively so that the valve 1 is rendered conducting 10 and valve 2 is then rendered non-conducting.

Thus the circuits may be used to generate pulses of a highly stable duration under the influence of controlling impulses the duration of which need not be highly stable nor the same as that of the generated impulses. Also the circuits may be employed in free-running manner, (i. e. no controlling impulses being applied), so as to generate pulses of highly stable duration and of period determined by the time constant of the coupling circuit associated with the control electrode of valve 2, said control electrode being properly biased so that free-running oscillations are generated by the circuit. By biasing the control electrode of valve 2 sufficiently negative one stable state may be imparted to the circuit so that, if desired, said circuit may be employed as a so-called "flip-flop" circuit generating a single impulse under the influence of a single applied impulse, the duration of the generated impulse being independent of the duration of the applied impulse.

I claim:

1. A circuit for generating electrical impulses, comprising a first and a second electron discharge valve each having a cathode, a control electrode and an output electrode, means for connecting said output electrodes to a power supply, means coupling the output electrode of the first valve to the control electrode of the second valve, means for periodically rendering the first valve nonconducting to render the second valve conducting while the first valve is non-conducting, a delay line connected to both of said cathodes, and means for feeding to said delay line impulses set up at the cathode of said second valve when the latter is rendered conducting, and means for feeding said impulses after traversing said delay line to the cathode of said first valve to render said valve conducting to control 50 the duration of said generated impulses.

2. A circuit for generating electrical impulses, comprising a first and a second electron discharge valve each having a cathode, a control electrode

and an output electrode, means for connecting said output electrodes to a power supply, means coupling the output electrode of the first valve to the control electrode of the second valve, an impedance in the cathode lead of each of said valves, means for periodically rendering the first valve nonconducting to render the second valve conducting while the first valve is nonconducting, a delay line for determining the duration of said electrical impulses having a pair of input terminals with one terminal connected between one impedance and the cathode of one of said valves and the other connected between the other impedance and the cathode of the other of said valves, the end of said delay line remote from said input terminals being open-circuited, whereby when said second valve is rendered conducting a control impulse set up at said second cathode is propagated along said delay line and is applied to the cathode of the first valve to render it conducting.

3. A circuit for generating electrical impulses, comprising a first and a second electron discharge valve each having a cathode, a control electrode and an output electrode, means connecting said output electrodes to a power supply, means coupling the output electrode of the first valve to the control electrode of the second valve, means for periodically rendering the first valve nonconducting to render the second valve conducting while the first valve is nonconducting, a delay line for determining the duration of said electrical impulses, said delay line having a pair of input terminals with one terminal connected to the cathodes of said valves, whereby the delay line provides an impedance common to the cathode circuits of said valves, the end of said delay line remote from said input terminals being short-circuited, whereby when said second valve is rendered conducting a control impulse set up at said second cathode is propagated along said delay line and applied to the cathode of the first valve to render it conducting.
